UNITED STATES PATENT OFFICE.

JOHN L. POPE, OF CLEVELAND, OHIO.

DESIGN FOR A HARNESS-BIT.

SPECIFICATION forming part of Design No. 13,554, dated January 30, 1863.

Application filed November 11, 1882. Term of patent 14 years.

To all whom it may concern:

Be it known that I, JOHN L. POPE, of Cleveland, in the county of Cuyahoga and State of Ohio, have invented and produced a new and original Design for Harness-Bits, of which the following is a specification, reference being had to the accompanying photographs, making a part thereof.

My invention relates to a novel design for cheek-pieces of harness-bits; and it consists in certain features of configuration, which will be hereinafter more particularly described and claimed.

In the photographs which accompany this specification, Figure 1 represents what is known to the trade as a "half-cheek" bit, and Fig. 2 as a "full-cheek" bit, both of which embody my invention.

Similar letters of reference in both views indicate like parts.

A is the bit proper, and is of the kind known as "snaffle-bits." B B are the rings or loops to which the reins are secured, and C C are the cheek-pieces. The rings and cheek-pieces, as usual, are formed together in one piece of metal.

I have produced a new design of cheek-piece, which will be found to be very pretty in general outline, the distinctive feature of which rests in the employment of two contiguous frame-like portions, the inner one, D, tapering from where it leaves the loop B, and curving just

as it meets the outer frame, E, which latter at this juncture is of pointed-arch shape, which arch-like figure has a contracted extension, o, 35 at its outer end. The inner edges of the frame D are so designed as to form in open-work a trefoiled figure, n, while the inner edges of the frame E form a figure somewhat resembling an ordinary urn, m. In those portions 40 of the cheek-pieces projecting below the mouth-piece or bit these urn-like figures referred to are shown inverted.

My invention may be applied to either half-cheek bits or full-cheek bits, and it is of course immaterial whether the bit be a snaffle or other known kind.

What I claim a Design Patent for is—

1. A harness-bit having the cheek-piece composed of two contiguous frames, of substantially the form shown and described.

2. A harness bit the inner edges of the cheek-piece of which are so disposed as to form two figures, substantially like n and m.

3. A harness-bit with loops and cheek-pieces having the general contour shown and described.

In witness whereof I have hereunto set my hand this 3d day of November, 1882.

JOHN L. POPE.

In presence of—

WALTER A. BIDDLE,
GEORGE F. EBERHARD.
